UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

THREAD-FASTENING MACHINE.

Application filed December 20, 1919. Serial No. 346,400.

The present invention relates to certain improvements in thread handling machines and more particularly to machines of the general type shown and described in the patent to La Chapelle, No. 1,185,108, dated May 30, 1916.

These machines are designed for temporarily securing together the insole and upper of a lasted shoe by the insertion of separate thread fasteners therethrough. Each fastening consists of two loops of thread passed through the work from the same side and with the first loop of thread interlocked with the second loop upon the opposite side.

10 The stitch-forming instrumentalities employed for this purpose comprise generally a curved eye-pointed needle for forming the two loops of thread and a cooperating thread finger which serves to pass the first loop of thread through the second.

It sometimes happens with these machines, especially where a waxed thread is used, that the first loop of thread does not become disengaged from the thread finger when the latter is withdrawn, and, in consequence, fails to interlock with the second loop in the desired manner. It is, therefore, one object of the present invention to provide certain improvements in a machine of this character for insuring the formation of a perfect stitch in every instance.

With this object in view, one feature of the invention, then, contemplates the provision in a thread handling machine, comprising a needle actuated to pass two loops of thread through the work from the same side and a reciprocating loop carrier for engaging the first loop of thread and passing it through the second upon the opposite side of the work, of a loop retaining member for engaging behind the first loop of thread when the thread finger has advanced to prevent withdrawal of the loop with the thread finger.

A further feature of the invention consists in the combination with a reciprocating thread finger of a normally stationary loop retaining member extending across the path of the thread finger and adapted to engage behind a loop of thread carried thereby.

A still further feature of the invention consists in the combination with a recipro-

cating thread finger adapted to carry a loop 55 of thread, of a loop retaining member yieldingly supported adjacent the path of movement of the thread finger in such a manner that it will engage behind a loop of thread carried thereby without bearing 60 upon the thread finger with any substantial pressure. With this feature, the loop retaining member rides lightly over the loop of thread as the thread finger is advanced and thereafter drops down behind the 65 thread loop to insure that it shall be cast off from the thread finger when the latter is retracted.

In the accompanying drawings illustrating the preferred form of the invention 70 Fig. 1 is a front elevation of a machine embodying the improved features of the invention; Fig. 2 is a detail illustrating a front elevation of the improved loop retaining device and cooperating stitch-forming instrumentalities; Fig. 3 is a side elevation of the mechanism shown in Fig. 1; and Figs. 4 to 8 inclusive are diagrammatic representations of that portion of the formation of a stitch in which the loop retaining 75 device cooperates with the thread-forming instrumentalities.

The machine shown in the illustrated embodiment of the invention is provided with a curved eye-pointed needle 10 actuated to 80 pass two separate loops of thread through the work from the same side, and a reciprocating thread finger 11 designed to engage with the first loop of thread and pass it through the second upon the opposite side 85 of the work. The thread finger 11, as illustrated in Fig. 1 of the drawings, is adjustably mounted upon a reciprocating slide 12 actuated from the usual rotary cam to advance and retract the thread finger in a 90 straight line path as fully disclosed in the patent to La Chapelle referred to. During the formation of the stitch, the work is held in position by the usual back gage 13 and channel guide 14. As will be observed 95 upon an inspection of Figs. 4 to 8 inclusive, the needle 10 is first actuated to pass a loop of thread (a) through the work, which is engaged and held by a tip 15 formed upon the thread finger 11. Thereafter the needle is jogged laterally and actuated to pass a second loop of thread (b) 100 through the work. It will be evident from

an inspection of Fig. 4 that the second advancing movement of the needle is greater than the first so that a straight line movement of the thread finger, when advanced, 5 will cause the end to pass between one side of the loop (b) and the shank of the needle as shown in Fig. 5, carrying the first loop of thread through the second. Thereafter 10 the thread finger is withdrawn simultaneously with the rearward movement of the needle to set the stitch, leaving the loop of thread (a) interlocked with the loop of thread (b).

The present invention aims to insure the 15 retention of the first loop of thread within the second, and to this end, a loop retaining member or cast-off 20 is designed to engage behind the loop (a) of thread after it has been passed through the loop (b) by the 20 thread finger 11. In the illustrated embodiment of the invention, the cast-off is in the form of a pointed arm extending across the path of movement of the thread finger and is supported in such a manner with respect 25 to the second advancing movement of the needle that the thread finger passes first through the second loop of thread and then beneath the arm which rides lightly over the first loop of thread on the thread finger. 30 When the thread finger is completely advanced, the operative end of the arm is positioned behind the loop of thread on the finger in a manner to prevent withdrawal of the loop with the finger.

35 As shown in the drawings, the member 20 extending across the path of movement of the thread finger is pivotally supported to rock toward and away from the thread finger. This pivotal connection is formed by 40 an integral stud 22 which is received within a bearing sleeve 23 adjustably connected to a bracket 24 through a tongue 31 and dovetailed groove 30 formed respectively upon the sleeve and bracket as indicated in Fig. 3. 45 The bracket 24 is capable of vertical adjustment with respect to the machine frame through bolt and slot connections indicated at 25, and in addition, the bracket is provided with an elongated slot 21 which causes 50 the tongue 31 to be gripped positively upon tightening the bolt 25. Thus it will be seen that the loop retaining member has a capacity for both vertical and lateral adjustments to locate it properly with respect to the path 55 of movement of the thread finger.

According to the present construction, the 60 loop retaining member is designed to be normally supported with its operative end in a position to just clear the thread finger as the latter moves thereunder. This position of the loop retaining member is maintained yieldingly in order that it may ride over the thread carried by the finger 11. In order to yieldingly support the arm 20 in 65 this position, a tension spring 26 is connect-

ed between a collar 28 clamped upon the end of the stud shaft 22 and a pin 27 mounted on the machine frame. The collar 28 is clamped to the stud shaft 22 by a set screw 33 and is provided with a tail 34 adapted to 70 engage with the front face of the bracket 24 to determine the normal position of the arm 20. It will be evident that by loosening the collar 28 on the stud shaft 22, the vertical position of the arm 20 may be varied 75 as desired to locate the pointed end of the arm accurately with relation to the path of movement of the thread finger.

The operation of the loop retaining member in conjunction with the thread finger 80 is shown clearly in Figs. 4 to 8 inclusive of the drawings. As the thread finger advances, in Fig. 5, the loop retaining member first engages lightly and rides over the loop (a) of thread held thereby. When the thread finger is completely advanced, as shown in Fig. 6, the end of the loop retaining member has dropped down behind the loop of thread in such a position that upon the withdrawal of the thread finger, in Fig. 7, the loop of thread is engaged and held by the pointed end of the arm 20. When the take-up acts to draw the second loop of thread into the work, as shown in Fig. 8, 90 the first loop is drawn off of the pointed end of the member 20. This construction thus forms a simple and effective means for preventing the withdrawal of the locking loop with the loop carrier. 95

While it is preferred to employ this specific 100 construction and arrangement of parts shown and described, it will be understood that this construction and arrangement is not essential except so far as specified in the claims, and may be changed or modified 105 without departing from the broader features of the invention.

The invention having been described, what is claimed is:

1. A thread handling machine comprising- 110
a needle, means for actuating the needle to pass two loops of thread through the work from the same side, a thread finger for engaging the first loop of thread and passing it through the second upon the opposite side of the work, and a member for engaging behind the first loop of thread when the finger is in an advanced position to prevent withdrawal of the loop with the thread finger. 115

2. A thread handling machine comprising- 120
a thread finger, means for reciprocating the thread finger, a loop retaining member extending across the path of movement of the thread finger, and means for yieldingly supporting the member in position to engage behind a loop of thread carried by the finger when the latter is in an advanced position. 125

3. A thread handling machine compris- 130

ing a thread finger, means for reciprocating the thread finger, a loop retaining member pivotally supported above the thread finger and adapted to engage with and ride over a 5 loop of thread when advanced by the finger, and means for yieldingly supporting the member in operative position adjacent the upper face of the thread finger.

4. A thread handling machine comprising 10 a reciprocating loop carrier, an arm extending across the path of the loop carrier, and means for yieldingly retaining the arm in position to engage behind a loop of thread on the carrier when the latter has reached 15 an advanced position.

5. A thread handling machine comprising 20 a loop carrier, means for advancing and retracting the loop carrier, a normally stationary loop retaining arm for casting off a loop of thread from the carrier when the latter is retracted, and means independent of the carrier for determining the operative position of the arm.

6. A thread handling machine comprising 25 a loop carrier, means for advancing and retracting the loop carrier, a normally stationary loop retaining member supported in

proximity to the path of movement of the carrier and adapted to cast a loop of thread off the carrier when the latter is retracted, 30 and means for supporting the loop retaining member having provision for vertical and transverse adjustment with respect to the path of movement of the carrier.

7. A thread handling machine comprising 35 a loop carrier, means for advancing and retracting the loop carrier, a pivoted arm extending across the path of the loop carrier, and a tail adjustably connected with the arm and adapted to contact with a fixed 40 portion of the machine frame to determine the operative position of the arm with respect to the path of movement of the carrier.

8. A thread handling machine comprising 45 a loop carrier, means for advancing and retracting the loop carrier, an arm extending across the path of movement of the carrier, an adjustable bracket, a shaft projecting from the arm and journaled within the bracket, a collar clamped to the shaft, and 50 a spring connected with the collar and adapted to yieldingly retain the arm in an operative position.

FRED N. LA CHAPELLE.
